UNITED STATES PATENT OFFICE

EMMA SHERWOOD, OF NEW YORK, N. Y.

CUSHIONING AND HOLDING SUPPORT FOR TYPE-WRITERS.

1,129,526.

Specification of Letters Patent. Patented Feb. 23, 1913.

Application filed March 31, 1913. Serial No. 757,835.

To all whom it may concern:

Be it known that I, EMMA SHERWOOD, a citizen of the United States, residing at New York, in the county of New York and State of New York, have invented certain new and useful Improvements in Cushioning and Holding Supports for Type-Writers, of which the following is a specification, reference being had therein to the accompanying drawing.

My invention relates to cushioning and holding supports for typewriters and the like, the general object being to hold the machine securely upon its desk or supporting board while affording a cushioning effect obviating or lessening jar and noise.

Further objects are to provide the machine itself with a detachable cushion which may be used quite independently of holding the machine on the desk or supporting board; to provide for almost instantaneously attaching the machine to its support or detaching it therefrom; and to provide devices which are inexpensive and practically unchanged by long use.

In the accompanying drawings, Figure 1 is a plan view of the devices, the typewriter frame or foot being omitted. Fig. 2 is a section on the line 2—2, Fig. 1, a portion of the machine frame being shown. Fig. 3 is a plan view of a portion of the device which is secured to the desk or board. Fig. 4 is a side elevation of that portion of the device which is carried by the typewriter machine itself.

In these views, A represents the board or desk top to which the typewriter is to be secured, and B a plate having a large central opening B^o and provided with bosses B' upon opposite sides of the latter and adjacent to the opening. Upon the bosses, respectively, rest two symmetrically placed arms C having their opposing inner margins curved to form approximately a semicircle of a radius materially smaller than that of the opening B^o. Through each arm, its boss and the board, in the rear of the center of the opening B^o, passes an attaching bolt D which serves as a pivot upon which the arm swings freely in a plane a little above the body of the plate B. When the machine is removed from the desk or board, these arms are normally held against stops D' so that their forward ends are widely separated while the rear portion of the in-

ner margin of each is brought well forward over the opening B^o as shown.

The part of the device carried by the machine includes a helical spring E having at its upper end a rigidly connected, centrally open horizontal member E' and at its lower end an integral coil extension flange or projecting base portion E². The upper as well as the lower of these members is conveniently formed by properly winding, nearly in a plane, the constituent rod of the helix. Upwardly through the opening in the upper end member of the spring passes a screw bolt F which bears a nut F' having a lateral arm F² for engaging the upper edge G of the socket member G' of the machine. By turning this screw from below by a screwdriver, or the like, inserted in the helix this engagement with the machine is made rigid and the machine is thus provided with a detachable cushion adapted to rest upon any plane surface, regardless of other devices.

The lower flange, or nearly plane spiral, has its outer turn slightly below the other parts so that it bears the entire weight, and this flange in itself furnishes a very sensitive and elastic cushion. Indeed in some cases, or in some machines, the helix is screwed into a tubular recess in the machine frame and serves merely for attaching, the cushioning being secured by the flange alone. In such case the omission of the screw or bolt and its nut does not destroy the usefulness of the device, although I prefer to employ the positive attachment in all cases.

To attach the machine to a board provided with the devices first described, the cushion is placed upon the front portion of the plate B between the arms C and the machine is pushed rearward, the cushion sliding on the plate. When the helix strikes the rear portions of the arms the latter are swung on their pivots into position to clasp the helix loosely above the annular external flange formed by its lower member, and as the latter reaches its rearmost position gravity carries it downward in the opening in the plate until its base rests upon the board where it serves as an unchanging cushion which the side of the opening, in which it lies, prevent from material lateral movement in any direction. The distance of the flange from the arms now directly above it

is substantially equal to the thickness of the body of the thin plate B, and the machine may be lifted vertically through this short distance. When so lifted it may be drawn forward freely and be thereby detached, but it cannot move materially in any other direction. In ordinary use there is nothing to lift the machine thus and move it forward while lifted, and where the desk is arranged for causing the machine to disappear, the tendency is to move the machine rearward and not forward. It follows that while the machine may be intentionally detached or attached almost instantly, under all possible operating conditions it is secure against accidental or undesired movement to a material extent in any direction. It is also obvious that the devices carried by the machine form a very useful and complete cushion for attachment to any ordinary machine. The word helix is herein used for convenience to designate the body of the spring, but it is intended to designate any analogous spring whether or not it is of uniform diameter.

What I claim is:

1. In a clamp for a flanged typewriter foot, the combination with a suitable support, of a plate fixed to the support and having a foot-receiving opening, two opposing jaws co-acting with the plate mounted pivotally above the plate upon opposite sides, respectively, of said opening, normally open forwardly and extending toward each other partially across the rear portion of said opening in the path of a foot moved rearwardly over the plate to position for dropping into said opening.
2. In a clamp for a flanged typewriter foot, the combination with a plate provided with a foot-receiving opening and adapted to be fixed to a plane support, of co-acting curved jaws pivoted upon opposite sides of said opening, respectively, to swing in a plane parallel to that of the plate and each having its rear end extending, when the jaws are open, partially across the rear portion of the opening, and springs constantly urging the jaws to open position; whereby a

foot moved rearwardly over the plate between the open jaws strikes the extensions of the jaws thereby swinging the jaws to closed position and permitting the foot to drop into the plate opening.

3. In a clamp for a flanged typewriter foot, the combination with a plate having a foot-receiving opening, of curved jaws pivoted to the plate on opposite sides of said opening to swing in a plane parallel to that of the plate, each when closed extending partially across the opening in both front and rear of a foot centrally located therein, and each when in open position having its rear portion in front of the position of the same part when in closed position; whereby a foot moved rearwardly between the open jaws strikes the extensions of the jaws thereby swinging the jaws to closed position and permitting the foot to drop into the plate opening, and whereby a foot raised out of said opening and moved forwardly between the jaws strikes the forward portions of the jaws and swings them to open position permitting the foot to pass forward out of engagement with the jaws.

4. In a clamp for a flanged typewriter foot, the combination with a suitable support, of a thin plate fixed to said support and provided with an opening into which a typewriter foot of less diameter may drop when moved along the plate, two normally open jaws pivoted between their ends on opposite sides, respectively of said opening to swing in a plane parallel to the plane of the plate, above said plate, each extending at its rear end into the path of a foot moving rearwardly between the two and adapted to be closed, clamping the foot, by pressure of the latter against their rear ends as it moves rearwardly between the jaws toward the center of the opening and stops limiting the opening movement of the two jaws.

In testimony whereof I affix my signature in presence of two witnesses.

EMMA SHERWOOD.
